FRED S. CARR, OF NEWTON, MASSACHUSETTS, ASSIGNOR, BY MESNE ASSIGNMENTS, TO UNITED-CARR FASTENER CORPORATION, OF CAMBRIDGE, MASSACHUSETTS, A CORPORATION OF MASSACHUSETTS

FASTENER

Application filed December 30, 1926. Serial No. 157,966.

My invention aims to provide improvements in flush type fasteners.

In the drawings, which illustrate a preferred embodiment of my invention:—

5 Figure 1 is an elevation of a three-side lock flush type fastener, as used for securing a curtain to a vehicle;

Fig. 2 is a section on the line 2—2 of Fig. 1, being partly in elevation;

10 Fig. 3 is a rear elevation of a curtain with the stud attached;

Fig. 4 is a section on the line 4—4 of Fig. 2, showing the relation of the head and neck of the stud with the socket;

15 Fig. 5 is a section on the line 5—5 of Fig. 1, showing one manner of attaching the stud to its support;

Fig. 6 includes a front, a sectional and a rear view of the socket; and

20 Fig. 7 is a side elevation of the socket as it appears before attachment to a support.

The fastener illustrated in the drawings is a three-side lock, flush type fastener, the stud being locked with the socket against 25 separation by lateral stress transverse to the axis of the fastener. It is also locked against separation by an outward pull, except when a pull is exerted at a predetermined side thereof. The socket is countersunk into its

30 support so that it is substantially flush with the outer face of the support, as shown in Fig. 2. The socket is not necessarily limited to use with a stud of the type shown, but may be used with other types.

35 Referring now to the specific embodiment of my invention, as shown by the drawings, I have illustrated a stud member having a base plate 1 (Figs. 2 and 3) from which is

30 pressed a boss providing the head 2 of the stud. This boss is preferably oval-shaped in cross-section and is divided lengthwise by a slot 6 to provide two contractible and ex-

40 pansible portions 2^a and 2^b, as best shown in Figs. 2 and 3. The portion 2^a is cut by

45 a semi-circular slit 3 located adjacent to the

base plate 1 of the stud (Figs. 2 and 4) to provide a neck 4 and shoulder 5 for cooperation with a socket, as shown in Fig. 2. The portion 2^b is neckless and shoulderless for purposes more fully hereinafter described. 50 The ends of the slot 6 terminate in the base plate 1 and are enlarged (Fig. 3) to provide openings 7—7 between which portions 8 of the base plate are located. These portions 8 are located at the points where the shoulder portion 2^a and shoulderless portion 2^b join the base plate 1 and aid materially in permitting free bending of the base plate at the portions 8 during contraction and expansion of said boss portion. 55

60 The stud may be secured to a support in any suitable manner, but I have shown it secured to a flexible medium, such as a curtain 9, by means of an attaching plate 10 located at the front face of the curtain and having prongs 11 passing through a plate 12 and then through the curtain 9 and base plate 1 (Fig. 5). The prongs are then clenched against the base 1, as shown in Figs. 3 and 5. 65

70 The plate 12 prevents the prongs from tearing through the curtain and covers the holes made in the curtain for the passage of the prongs.

75 The socket, as shown in Figs. 2, 6 and 7, is pressed from sheet metal to provide a casing 13 having at one end a stud-receiving aperture 14 surrounded by the wall 15. A flange 16 is provided, adjacent the end presenting the aperture, to prevent the casing 80

from passing entirely through the aperture 17 in the socket support 18, as shown in Fig. 2. The casing beyond the flange is formed of several resilient fingers 19 having inbent 85

20 ends 20, which terminate about an aperture 21. The inbent finger portions pass through the aperture 17 in the support 18, and extend beyond the inner face of the support so that they may be bent outwardly and grip 90

the wall of the aperture 17 and prevent the

socket from being pulled loose from its support.

The means for expanding the inner portion of the casing is in the form of a tapered screw 22, which is assembled within the casing before the inwardly bent portions 20 are pressed into position. Normally, the tip end of the screw extends into the aperture 21 (Fig. 6) so that a screw driver or other suitable tool (not shown) may be inserted through the stud receiving aperture 14 to engage the slot 23 in the head 24 of the screw and turn the screw in a clockwise direction. As the screw turns, the ends of the inbent portions 20 accommodate themselves to the thread of the screw so that, as it feeds forward, the fingers are spread so that the casing is positively secured to the support 18, as best shown in Fig. 2.

To exclude dust and dirt from the casing, I provide a closure plate 25, which is normally pressed forward by a spring 26 to close the aperture 14, as shown in Fig. 6. When such a plate is used, a tool cannot be engaged directly with the slot 23 and therefore I have provided means for engagement between the closure plate and the screw, in the form of a depressed portion 27, forming a groove at one side of the closure plate and a boss at the other side, for cooperative engagement in the slot 23 in the head 24 of the screw, as shown in Fig. 6. Thus, a tool may be inserted in the slot in the closure plate, and, when turned, will also turn the screw for expanding that portion of the casing which lies beyond the inner wall of the support 18. The screw 22 may be disengaged from the inbent portions of the fingers 19, to permit removal of the socket, by turning the screw and closure plate 25 in a contra-clockwise direction.

The guiding pieces 28 (Figs. 6 and 7) at the sides of the casing and between the fingers 19, are parallel with the axis of the socket and provide means for guiding the closure plate when moved axially. These guiding pieces 28 do not bend outwardly when the fingers 19 are spread to affix the casing 13 to the support 18.

When the stud and socket are engaged, the wall 15 of the socket contacts with the neck 4 of the stud and the shoulder 5, formed by the slit 3, contacts with the inner face of the material of the socket which surrounds the stud-receiving aperture 14, as clearly shown by Figs. 2 and 4. In this position of engagement with the socket, the stud is locked against separation therefrom by stresses exerted upon the curtain at those sides of the stud where the shoulder 5 is provided. The fastener may be separated only by pulling outwardly on the curtain at the lower side of the stud or adjacent to the neckless portion 26 which provides a continuously curved 65 surface, thus permitting the stud to be tipped

so that the shoulder 5 may be tipped out of engagement with the socket.

The upper portion of the stud cannot yield sufficiently to permit separation of the fastener when lateral stress is exerted upon the curtain, but the lower portion may yield sufficiently to permit the stud to be tipped about the fulcrum provided between the shoulder 5 and the wall 15 of the socket, when the lower edge of the curtain 9 is pulled outwardly.

Reference is hereby made to applicant's co-pending application Serial No. 81,863, filed January 16, 1926, which contains claims generic to the invention illustrated and described in my present application.

My invention is not limited to the illustrative embodiment thereof shown and described.

I claim:

1. A separable fastener comprising, in combination, a socket having a stud-receiving aperture surrounded by a wall, a cooperating stud having a base, a boss portion extending from said base, said boss portion being entirely divided by a slit to provide two contractile and expansible portions, one of said portions being neckless and the other of said portions having a neck for engagement with the wall surrounding the aperture of the socket to secure the stud and socket together.

2. A separable fastener comprising, in combination, a socket presenting a stud-receiving aperture surrounded by a wall, a cooperating stud having an oval shaped boss portion provided with a horizontal slit to divide said boss portion into two contractile and expansible portions and a shoulder formed on one of said contractile and expansible portions for interlocking engagement back of said wall surrounding said aperture when said stud and socket are engaged thereby to prevent separation of the fastener by stresses exerted adjacent to said shoulder and the other portion being shoulderless whereby said fastener may be separated by a pull adjacent to the shoulderless side of the fastener.

3. A fastener socket comprising a casing presenting at one end thereof an inwardly extending face surrounding a stud-receiving aperture, and at the other end a plurality of expansible portions, and threaded means assembled as part of the socket prior to attachment to a support and adapted to engage and expand said expansible portions to secure the socket to a suitable support.

4. A fastener socket comprising a casing adapted to be inserted through an aperture in a suitable socket support, said casing presenting at the inner side of the support resilient means adapted to be expanded positively to secure the casing to the support and a screw assembled within the casing prior to attachment to a support for threaded en-

gagement with said resilient means to expand the same.

5. A fastener socket comprising a casing adapted to be inserted through an aperture in a suitable socket support, said casing presenting at the inner side of the support, inbent resilient means adapted to be expanded positively to secure the casing to the support and a tapered screw assembled within the 10 casing prior to attachment to a support for threaded engagement with said resilient means to expand the same.

6. A fastener socket comprising a casing inserted through an aperture in a suitable 15 support, said casing presenting an aperture at the outer side of the support and presenting inbent expansible portions at the inner side of the support, a screw having its head within said casing, a closure plate for said aperture and means whereby said closure plate 20 may be interlocked with the head of said screw so that rotation of said closure plate will rotate said screw to expand said inbent portions and positively secure said casing to the support.

7. A fastener socket comprising a casing inserted through an aperture in a suitable support, said casing presenting an aperture at the outer side of the support and presenting inbent expansible portions at the inner side of the support, a tapered screw having its head within said casing, a closure plate for said aperture and means whereby said closure plate may be interlocked with the 35 head of said screw so that rotation of said closure plate will rotate said screw to expand said inbent portions and positively secure said casing to the support.

8. A flush type fastener socket comprising 40 a casing presenting a stud-receiving aperture at one end thereof, a flange adjacent to the same end, a plurality of inbent portions extending from said flange to form the inner portion of said casing, a screw for expanding 45 said inbent portions to secure the casing to a support and closure means slidable relative to said casing for closing said aperture to prevent entrance of dust and dirt when a stud is not engaged with said socket, means for 50 guiding said closure means, and interengaging means provided between the closure means and screw whereby, when said closure means is turned, said screw may be turned.

9. A socket comprising a casing 13 having 55 a flange 16 at one end thereof and a stud-receiving aperture 14 at the same end as the flange 16, expansible means 20 extending from said flange and threaded expanding means 22 forming part of the fastener socket and 60 adapted to be moved axially relative to the casing to engage and expand the expansible means and secure the socket to a support 18, said threaded expanding means being adapted to be rotated to disengage it from the 65 expandable means.

10. A snap fastener member comprising a casing having means at one end thereof for engagement with a cooperating snap fastener member and having at the other end a plurality of expansible portions and a notched expanding element assembled as a part of the fastener member before the fastener member is attached to a support, said expanding element being movable axially relative to the expansible portions thereby to expand them and secure the fastener member to a support.

In testimony whereof, I have signed my name to this specification.
